CAP APPLYING MACHINE

John J. Gaynor, Delphi, Ind., assignor of one-half to Arthur I. Risser, Chicago, Ill.

Application February 27, 1933, Serial No. 658,879

24 Claims. (Cl. 226—84)

This invention relates to container capping machines, and more particularly pertains to bottle crowners as employed in association with container or bottle filling machines.

5 One object of the invention is to provide such a machine of the simplest construction that will expedite the capping of containers in order to increase the output of the filling machine. Another object is to provide such a machine that will 10 transfer containers thereto from the filling machine and cap same very soon thereafter, for the reason that in the bottling of certain liquid or chemical products, that are subject to chemical change by exposure to atmosphere, it is important that the bottles are not open to atmosphere too long after leaving the filling heads of the filling machine.

In carrying out the invention, a capping machine is provided with two capping heads mounted to reciprocate together about a common axis. Means is also provided for transferring filled containers from the container conveying means of a filling machine and placing same alternately into cooperative relation with said capping heads to be capped during oscillation of the heads. The advantage of this construction is that fewer capping heads are required to cap containers at a given rate than would be required if the heads rotated about the axis, as in the common rotary type machine.

Other objects and advantages will become apparent by reference to the specification, claims and the accompanying drawings, in which:

Fig. 1 is a small diagrammatic view of the capping machine embodying the invention as arranged in cooperative relation with a well known type of rotary container filling machine.

Fig. 2 is a front view of the capping machine and a portion of the filling machine, with parts broken away and parts in section, and as viewed in Fig. 1, looking in the direction of the arrow 2.

Fig. 3 is a sectional plan view taken substantially on the line 3—3 of Fig. 2, with certain parts shown in full.

45 Fig. 4 is a sectional plan view taken substantially on the section line 4—4 of Fig. 2.

Fig. 5 is a sectional plan view taken on the section line 5—5 of Fig. 2.

50 Fig. 6 is a sectional elevation of Fig. 2, taken substantially on the section line 6—6 thereof.

Fig. 7 is a side view of a portion of the top end of the machine, as viewed in the direction of the arrow 7 in Fig. 2.

55 Fig. 8 is a detail vertical section taken substan-

tially on the section line 8—8 of Fig. 2, with parts omitted and parts shown in full.

Fig. 9 is a back view of the central portion of the capping machine, as may be taken on the section line 9—9 of Fig. 6.

Fig. 10 is an enlarged plan sectional view of Fig. 2, taken on the section line 10—10 of said figure.

Fig. 11 is an enlarged vertical section of Fig. 6, taken substantially on the section line 11—11 of said figure.

Fig. 12 is a plan section taken on the section line 12—12 of Fig. 11.

Fig. 13 is a view similar to a portion of Fig. 10 with parts shown in changed position.

Fig. 14 is a view similar to Fig. 12 with parts shown in changed position.

Fig. 15 is a plan sectional view taken on the section line 15—15 of Fig. 11, with parts in changed position corresponding to the position of the parts in Fig. 14.

Fig. 16 is a vertical section taken substantially on the section line 16—16 of Fig. 14.

Fig. 17 is an enlarged detail view of a portion of Fig. 16, with parts omitted.

Referring to Fig. 1, the filling machine "A", somewhat diagrammatically illustrated, is of a well known type, in the rotary class. The filling machine comprises a circular filling tank 2 mounted on a central pedestal support 3 rotatably mounted in a suitable manner concentric with the tank, on the base support 4. Arranged equally spaced about the axis of the tank 2, and depending from the edge thereof, are vertically reciprocable filling heads 5 which are adapted to dispense liquid from the tank upon being raised therein.

The filling machine has means for conveying containers or bottles under the filling heads in cooperative relation therewith. Said conveying means includes a plurality of vertically disposed hollow plungers 6 equally spaced about the pedestal axis so that each plunger is below a filling head and central therewith. The plungers 6 are reciprocably mounted in bearings 7 in the periphery of the circular lateral extension 8 of the pedestal 3.

Removably secured at the top end of each plunger, is a stirrup 9 having an outwardly open yoke 10 for receiving the containers or bottles 11 to be filled, and in which the bottles are positioned under the filling heads, central therewith.

The filling machine rotates continuously in clockwise direction as viewed in plan, and as the plungers cross the station, indicated by the dot and dash line B—B in Fig. 2, the bottles are placed in

the stirrups by automatic means, not shown, and

105

Fig. 7 is a side view of a portion of the top end of the machine, as viewed in the direction of the arrow 7 in Fig. 2.

110

at which point the plungers are in lowered position. The plungers are then moved to raised position, causing the bottles to enter and raise the filling heads, in which position they remain during considerable movement of the filling machine to effect the filling of the bottles. The filled bottles are then lowered by the plungers before reaching the bottle receiving station, of the filling machine, and are then transferred to the capping machine embodying the invention. It may be stated that the plungers 6 are operated by a circular cam track 12 on the base support, and which is engaged by rollers 14 on levers 15 radiating from the pedestal on which they are pivotally connected, and whose other ends are connected pivotally through the intermediation of the connecting rods 16, to the plungers 6.

After the plungers 6 reach their lowered position, the filled bottles thereon are transferred, or deflected, sharply outward radially of the filling machine, between the spaced curved ends 20 and 21 of spaced bottle guide rails 22 and 23, onto an oscillating bottle support or table 24 so situated that the bottles are moved onto the table in a direction toward the axis thereof. In other words, the station at which the bottles are placed on the table is directly between the axis of the filling machine and the table axis, which station is indicated by the dot and dash line C—C on Fig. 10.

On the table is a radially extended block 25, in whose opposite sides are formed bottle positioning pockets 26 and 27, open in the direction of oscillation of the table. The table is operably connected with the filling machine to oscillate about 105 degrees, and the block is so positioned whereby the pockets 26 and 27 alternately register at the bottle receiving station of the table to receive a bottle at the limits of oscillation thereof. Above pockets 26 and 27 are capping heads 26a and 27a which apply caps to bottles in the pockets upon being carried around with the table, the bottles being guided so as to be held in the pockets during movement of the table, by the arcuate extensions 28 and 29 of the guide rails 22 and 23 respectively on each side of the table. Mounted on the guide rails 22 and 23 and positioned so as to extend into the path of the bottles, are leaf springs 30 and 31 respectively, which are deflected by the bottles passing thereby, but which prevent the bottles from returning with the table upon being capped, as best understood in Fig. 10. The bottles being capped on either side of the table are caused to push the capped bottles from the table, which are deflected therefrom by the guide bar 32 extending outward radially of the table, and then onto a shelf support 33 on which the guide bar is mounted. Cooperating with the guide bar on either side thereof are outward extensions 34 and 35 of the guide rails 22 and 23 respectively, for guiding the bottles in two separate rows, and which guide rails are mounted on the support shelf 33.

The table is oscillatably mounted on the shelf, in whose plane the table is located within the circular recess 34' thereof, and the table has a depending trunnion 35' received within a bearing 36 of the shelf. A thrust ball bearing 37 is interposed between the under side of the table and the top of the bearing 36, and engaging the other end of the bearing 36 is an end plate 38 at the end of the trunnion for holding the table in the plane of the shelf. The shelf is mounted, so as to be vertically adjustable, on the pedestal 39 comprising an upright cylinder portion 40 mounted on the base 4 and which is received in the depending

sleeve portion 41 of the shelf. A lock bolt 42 is provided in the sleeve portion for locking the shelf on the pedestal in adjusted positions.

The table is in driven connection with the filling machine by means of a vertical shaft 43 extending through an axial bore 44 in the table and its trunnion portion. In the side of the shaft is an elongated keyway 45 in which is received the key 46 in the table bore so that the shaft is connected to oscillate the table but is vertically adjustable in the bore. The shaft 43 extends below the table trunnion, and at the bottom end of which is a crank disc 47 having crank pin connection at 48 with one end of a connecting link 49. The other end of the connecting link is pivotally connected to the crank pin 50 of a crank arm 51 mounted at the bottom end of a vertical power shaft 52 extending upward through a bearing 53 in the shelf and whose top end is rotatably mounted in a bearing 54 in a support head 55 at the top end of the pedestal 39. On the power shaft 52 is a spur gear 56 in key connection with the keyway 56' extending along the side of the shaft for rotating same but permitting its vertical adjustment therein. The spur gear 56 is held between the bearing 53 of the shelf and an arm 57 mounted thereon for holding the gear in a fixed plane with respect to the shelf. Meshing with the gear 56 is a spur gear 58 rotatably mounted on a stub shaft 59 depending from the shelf and adjustably secured thereto. On the stub shaft and connected with the gear 58 is a smaller spur gear 60 meshing with a ring spur gear 61 mounted on the periphery of the lateral circular extension 8 on the pedestal 3 of the filling machine. It may be stated that the ring gear 61 serves as an operable connection with gear driving means, not shown, for rotating the filling machine as well as providing an operable connection therewith for the capping machine. The shaft 59 is adjustably secured to the shelf 33 by means of its upper reduced threaded end portion 59' which projects through an elongated slot 59² in the shelf that extends toward the axis of the ring gear of the filling machine, and on which reduced shaft end is received a washer 59³ and a nut 59⁴ for securing the shaft in adjusted positions along the slot. Thus upon assembling the capping machine with the filling machine, the shaft may be adjusted toward or away from the ring gear 61 to accommodate the proper size of gear 60, in regulating the operation of the capping machine in accordance with the number of bottle support plungers on the filling machine. The size of gear 60 in turn determines the proper ratio of the gears 56 and 58 to be employed. The gears and cranks just described are so proportioned and timed that as the bottles are transferred onto the table they are carried around alternately in opposite directions with the table during oscillation thereof.

The capping heads 26a and 27a mentioned briefly in the foregoing description will now be described. The capping heads each comprises a hollow cylindrical plunger 62 vertically disposed above its respective pocket so as to centrally register with a bottle therein. The plunger extends through and is reciprocably mounted in a bearing bore 63 in a cylindrical head or block 64 coaxial with the table and connected to oscillate therewith by the top end of the vertical shaft 43 being secured in the depending boss portion 65 of the head. The head 64 is oscillatably mounted in a bearing 66 in a bracket 67 mounted on the pedestal 39. The portion of the

pedestal on which said bracket is mounted is in the form of a sleeve 68 extending within the pedestal portion 40 and having a threaded portion 69 receiving a nut 70 engaging the top end of the 5 pedestal portion 40 for adjusting the capping heads to various sizes of bottles.

Across the top end of each plunger 62 is a plate 71 secured thereto by means of a plug formation 72 of the plate being in threaded connection 10 in the end of the plunger. Extending upward from the head 64 alongside of each plunger is a guide pin 73 which slidably projects through the plate for holding the plungers from rotating in their bearings. Each plunger is resiliently 15 held in raised position by a coiled compression spring 74 interposed between the plate, on which is a pin 75 projecting therein, and the head 64 in which is a recess 75' in which the other end of the spring is mounted. At the bottom end 20 of each plunger is a peripheral flange 76 for limiting upward movement of the plungers in their bearings.

Near the bottom of each plunger is a lateral cap receiving recess 77 for positioning a cap 78, of the 25 well known crown bottle stopper type, slightly eccentric in the plunger toward the axis of the head and with its open side facing downward. The cap receiving opening 79 of the recess extends toward the center of the head, and each plunger 30 is so operated that upon its respective bottle positioning pocket being located at the bottle receiving station of the table, the plunger is in raised position with its cap receiving opening in register with the cap discharge end 80 of a cap 35 magazine 81, of the gravity feed type, for directing a cap into the recess.

Upon movement of the table after a bottle is positioned in one of the pockets, the plunger of the capping head thereover is caused to be lowered, whereby the neck of the bottle enters the plunger and engages the cap so that the peripheral bead 82 about the bottle mouth is surrounded by the flared skirt 83 of the cap. As the plunger lowers further, the skirt of the cap becomes engaged within the conical bore portion 84 above the recess which effects the constriction of the cap skirt about the bead 82 about the bottle mouth, as the plunger is resiliently forced down over the bottle by means later described.

50 As a cap is forced into the conical bore portion of a plunger, it engages a spring pressed plunger head 85 slidably mounted in the short reduced bore portion 86 extending from the conical bore portion for holding the cap square with the bottle mouth and for insuring ejection of the 55 capped bottle from the capping head. The plunger head 85 has an upwardly extended stem 87 reciprocably mounted in the bore of a screw 88 extending through the plate 71 and in threaded connection with a lock washer 89 threaded in the bore of the hollow plunger. A coiled compression spring 90 surrounds the stem and is interposed between the lock washer and the plunger head which is normally held in lowered position, with 60 its bottom end forming the top wall of the recess 77, by the annular extended shoulder 91 of the head engaging the annular shoulder in the bore of the hollow of the capping head plunger, indicated at 92.

70 The cap magazine and its operable connection with the capping heads will now be described. The magazine is in the form of a closed sided chute in which the caps are guided in uniform single order, and extends from its discharge end 75 80 horizontally outward into a lower end portion

93 which is snugly supported in its plane in the outwardly opened chamber or recess 94 in the capping head support block 64. The chamber is formed outwardly flared laterally to permit movement of the support block with respect to the chute end, which end is held centrally positioned with respect to the block by the pivotal connection 95 at the axis of the block therebetween.

Between the bearing bore of each capping head plunger and the chamber 94 is a cap passage-way 96 for directing caps from the magazine discharge end into the recess of the plunger. The cap discharge end of the magazine is arcuately formed concentric with the capping head support block and extends very close to the side of a capping head plunger when in register therewith, whereby only the skirt of a succeeding cap at said end extends therebeyond. Between the cap passage-ways the wall portion of the chamber 94 is arcuately formed as at 97 to snugly close the magazine discharge end during oscillation of the capping head support and which also pushes back the succeeding cap at said end. In the event the succeeding cap is not pushed back before the plunger of the capping head is lowered, due to faulty timing of the elements, it is pushed back by the camming engagement with the outwardly and upwardly flared edge 98 of the ball of the plunger at the top of the opening when the plunger is lowered.

The cap magazine continues upward into an upright portion 99 which is in supply connection with a cap feeder device 100 mounted on the support head 55 which has operating means for feeding caps to the magazine in proper order. In as much as the cap feeder device forms no particular part of the invention, for the reason that other means could be employed to feed caps to the magazine, it is thought that a detailed description of said device is not necessary. However, it may be stated that the device is in driven connection with the power shaft 52 of the capping machine. The driven connection is effected by a worm gear 101 on the power shaft at the top end thereof and which meshes with a worm gear 102 on the end of a horizontal shaft 103 rotatably mounted in bearings 104 on the right side of the support head 55 as viewed from the front of the machine.

On the shaft 103 is a gear 105 meshing with a larger gear 106 thereover connected to one end of a shaft 107 mounted rotatable in spaced bearings 108 on the support head. On the shaft 107 is a sprocket 109 in driving connection with a sprocket 110 of the operating shaft 111 of the capping device through the intermediation of the sprocket chain 112.

Means for operating the capping heads will now be described. Located vertically reciprocable above the capping heads 26a and 27a, are plunger shafts 113 and 114 respectively, each shaft being slidably mounted in an elongated bearing 115 in the support head 55. Upon movement of a capping head from the station at which a bottle is placed thereunder, when being carried around with the table, its respective plunger shaft is caused to be lowered which has a roller 116 at its bottom end that engages a strike plate on the plate 71 of the head, whereby the head is moved to its lowered position when having been turned about 90 degrees from the bottle receiving station, in which position the capping head 26a is shown in Fig. 12. As the capping head continues on to its limit of oscillation, its plate 71 rides out from under the plunger shaft, as seen in Figs. 14 and 16, whereupon the head is returned to raised po-

145

150

sition by its spring 74, and out of connection with the capped bottle thereunder to prevent its returning to the bottle receiving station therewith.

Extending between the plunger shafts is a rock shaft 117 mounted in bearings 118 on the support head, and on which shaft is a spur gear 119 meshing on opposite sides with a longitudinal rack 120 on the side of each plunger shaft, for reciprocating the plunger shafts in alternation. For 10 resiliently oscillating the rock shaft, said shaft has a spur gear 121 mounted on its outer front end which meshes with rack teeth 122 on the bottom side of a connecting link or rod 123 slidably mounted in the guideway of a guide block 124 15 loosely mounted on the rock shaft. One end of the connecting link is fulcrumed on a crank pin 125 at one end of a crosshead or slide 126 slidably mounted for limited movement in the guideway 127 traversing the axis and in the side of a vertically disposed crank disc 128 which is mounted 20 on the forward end of the horizontal shaft 103. The cross head is confined for limited movement between a fixed stop block 129 at one end of the guideway and a stop block 130 adjustably mounted in the other end of the guideway. Interposed 25 between the adjustable stop block and the cross-head are two spaced apart compression springs 131 mounted on pins 132 extending from the stop block and whose other ends are received in recesses in the end of the cross-head. The crank pin of the cross-head is so situated that the springs 131 urge the pin with the head outward of the axis of the disc. The gear 121 is so proportioned with respect to the normal throw of the crank pin 125 of the cross-head that when the crank pin is on dead center with regard to the connecting link, on either side of the axis of the disc, a capping head is in pressure engagement with the cap on a bottle thereunder, which pressure is effected by the compression springs 131 caused by the inward movement of the cross-head after initial engagement of the capping head with the bottle, whereby the springs are compressed an amount indicated by the space 133 existing between the cross-head and the stop block 129 as 30 shown in Fig. 3. The advantage of this construction is that the same capping pressure is exerted on both the capping heads for the reason that the springs 131 are compressed in a like manner by the capping engagement of both heads with a bottle. For regulating the capping pressure of both capping heads, the adjustable stop block is adjusted by a set screw 134 threaded into a lug 135 in the guideway of the disc, which regulates pressure of the springs 131. 35

A conveyor or stationary table, not shown, may be situated along the side of the shelf support to receive the capped bottles therefrom, or the bottles may be taken from the shelf by hand or other means.

Having thus described my invention, I claim:

1. In a container capping machine, means for feeding caps in uniform single order, two cap applying devices relatively oscillatable about a common axis with respect to said feeding means and arranged whereby each device is alternately brought into cooperative relation with said means upon each oscillation thereof to receive a cap.

2. In a container capping machine, means for feeding caps in uniform single order, two connected cap applying devices mounted to oscillate about a common axis, each device having a cap receiving recess adapted to be brought into cooperative relation with said feeding means upon each oscillation of the device to receive a cap.

3. In a container capping machine having means for conveying containers in two rows of single order and means for feeding caps in uniform single order, the combination of two connected cap applying devices relatively oscillatable about a common axis with respect to said feeding means and arranged whereby each device is alternately brought into cooperative relation with the cap feeding means to receive a cap then moved into cooperative relation with a container on the conveying means to apply the cap thereto.

4. In a container capping machine having means for conveying containers in single order, means for feeding caps in single order, two cap applying devices mounted to oscillate about a common axis and arranged to be alternately brought into cooperative relation with the cap feeding means to receive a cap, and means for transferring the containers from the conveying means and placing them into cooperative relation with said capping devices alternately.

5. In a container capping machine in combination with means for conveying containers in single order, two cap applying devices mounted to oscillate about a common axis, and means for transferring the containers alternately into cooperative relation with said devices to be capped.

6. In a container capping machine, a horizontally oscillatable support element, two cap applying devices mounted vertically reciprocable on the support about the axis thereof, each device having a cap receiving recess, the support having a radial cap passage-way registering with the recess of each device in its raised position, and a gravity feed cap magazine having a discharge end into which said radial passages are brought into registration upon each oscillation of the support for feeding a cap into a recess.

7. The structure as defined in claim 6 including means for blocking the magazine discharge end when the recesses of both cap applying devices are out of registration therewith.

8. In a container capping machine, an oscillatable support element, two cap applying devices mounted on the support about the axis thereof, each device having a cap receiving recess, a gravity feed cap magazine having a discharge end into which the recesses are brought into cooperative registration alternately upon each oscillation of the support, and the support having a cap engaging abutment brought into blocking relation with the magazine discharge end when both recesses are out of cooperative registration with said end.

9. In a container capping machine, in combination with means for conveying containers in single order, an oscillating container support table, means for transferring the containers from the conveying means onto the table at a fixed station, the table having two container positioning pockets adapted to register at said station to receive a container transferred thereto, and two cap applying devices, each reciprocably mounted above a pocket and adapted to be brought into capping relation with the container therein upon leaving said station.

10. In a container capping machine, an oscillating container support table, means for placing containers onto the table at a fixed station, the table having two container positioning pockets adapted to register at said station upon each oscillation of the table to receive a container, a cap applying device reciprocably mounted above each pocket and adapted to be moved into

- capping relation with a container therein upon leaving said station.
11. In a container capping machine, an oscillating container support table, means for directing containers onto the table at a fixed station, the table having two container positioning pockets adapted to register at said station at each oscillation of the table to receive a container, and means for applying a cap to the container upon leaving said station. 80
12. In a container capping machine in combination with means for conveying containers in single order, two cap applying devices mounted to have movement together back and forth between fixed limits, and means for transferring the containers from the conveying means and placing them alternately into cooperative relation with said devices to be capped. 85
13. In a container capping machine, an oscillating container support table having means for positioning two containers thereon about its axis, two capping devices reciprocably mounted above the table, connected to oscillate therewith and each reciprocable into cooperative capping relation with a container on the table, means for directing containers to the positioning means from a common station, and means for operating the capping devices upon their respective containers being positioned on the table. 90
14. In a container capping machine, an oscillating support element, two cap applying devices mounted on the support about the axis thereof, and means for feeding caps from axially of the support alternately to said devices at each oscillation of the support. 100
15. In a container capping machine, an oscillating support element, two cap applying devices mounted on the support about the axis thereof and adapted to register at a fixed station at each oscillation of the support, and means for feeding caps from axially of the support to said devices when at said station. 105
16. The structure as defined in claim 14 including means for placing containers into cooperative capping relation with said capping devices after receiving a cap. 110
17. The structure as defined in claim 15 including means for placing containers into cooperative capping relation with said cap applying devices upon leaving said station. 115
18. In a container capping machine in combination with means for conveying containers in single order to be capped, an oscillating support element, two cap applying devices mounted on the support about the axis thereof and adapted to register at a common station at each oscillation of the support, means for feeding caps to the devices at said station, and means for transferring the containers from the conveying means and placing them alternately into cooperative relation with the cap applying devices after leaving said station. 120
19. In a bottle crowner, two reciprocably mounted capping heads having means for applying crowns to containers under pressure engage- 125
- ment therewith when reciprocated, an oscillatably mounted driven shaft operably connected with said heads to reciprocate same alternately, and means for resiliently oscillating said shaft. 130
20. In a bottle crowner, two reciprocably mounted cap applying devices having means for applying crowns to containers under pressure engagement therewith when reciprocated, a driven oscillating shaft operably connected with said heads to alternately reciprocate same, a power shaft, a cross head mounted at the end of the power shaft to have limited slideable movement transversely of its axis, a spring urging the cross head in one direction, a crank pin on the cross head and a connecting link pivotally connected to the crank pin and operably connected with the driven shaft to oscillate same upon rotation of the power shaft. 135
21. In a container capping machine, an oscillating table having two container positioning pockets arranged about its axis and adapted to register at a common station at each oscillation of the table, means for placing containers in said pockets at said station, a cap applying device disposed above each pocket, connected to oscillate with the table and mounted to reciprocate into capping relation with a container upon leaving said station, means for operating the devices, and means for ejecting the capped containers from the pockets. 140
22. In a container capping machine, two devices, each device mounted movably and having in association therewith means for applying a cap to a container upon pressure engagement therewith when moved in a given direction, driven operating means operably connected with the devices to move same in their respective said given directions in alternation, and means for resiliently driving said operating means. 145
23. In a capping machine, a cap magazine having a cap discharge end, an element at said end and having a portion for blocking the end in blocking the passage of the caps, said magazine and element mounted to have relative movement back and forth between fixed limits whereby said portion intermittently blocks the end intermediate the limits of its relative movement for allowing intermittent discharge of the caps, and two cap applying devices operably associated with said element whereby upon its relative movement cooperative relation is established alternately between the devices and the discharge end in feeding caps to the devices. 150
24. In a capping machine, a support element, two cap applying devices mounted on the support, each device having a recess for receiving a cap, a cap magazine having a discharge end, said support and magazine arranged to have relative movement back and forth between fixed limits whereby cooperative registration is established alternately between the recesses of the devices and the discharge end, and the support having a portion formed to block the discharge end when the recesses of both devices are out of registration therewith. 155

JOHN J. GAYNOR.
